Primary Examiner — Susan Moon Lee*(74) Attorney, Agent, or Firm* — Brinks Hofer Gilson & Lione(57) **CLAIM**

I claim the ornamental design for a memory card, as shown and described.

DESCRIPTION

FIG. 1 is a front perspective view of a memory card of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken line showing of memory card is included for the purpose of illustrating environment and forms no part of the claimed design. Additionally, the unevenly broken lines in the drawings define the limits of the claimed design.
